FILM APPLICATOR

William H. Biddle, Vancouver, British Columbia,
Canada

Application October 18, 1947, Serial No. 780,711

13 Claims. (Cl. 91—30)

1

This invention relates to improvements in film applicators.

This device is designed to apply a thin film or coating of liquid or semi-liquid material, such as paint, varnish, lacquer and the like. The applicator is particularly designed for use in the paint industry in which it is necessary to compare the color and opacity of one batch of paint or the like with another. In order to do this, it is necessary to form a layer or film of the two batches side by side in order that they may be tested and examined. It is essential that these films be of uniform and predictable thickness. Where two or more films are to be compared as to color, opacity and the like, it is essential that they be applied at the same time with exactly the same treatment on the same surface edge to edge in a straight line without merging.

As the colors and gloss of paints, lacquers and the like undergo progressive change during their drying periods, the importance of simultaneous application is apparent. The characteristics of the materials may also be affected by the treatment the film receives during application. For example, if the film is applied by a brush, the number of strokes used might change its characteristics somewhat.

It is highly desirable that the panels or sheets on which the films are applied be of such a nature that they may be easily stored for future reference. In the paint industry, the production of each day is tested in this manner and the panels or sheets should be filed away as a record.

The usual method of application of such films has been by brush or by spray-gun and where an attempt has been made to produce a finite film thickness, it has usually been done by repeated weighing and brushing or spraying until a calculated weight has been reached. This method does not ensure uniform thickness over the whole area and it may be very inaccurate due to the evaporation of volatile solvent during the time taken for application. Where two or more films are to be applied for comparison it is practically impossible to satisfy the requirements of simultaneous application, equal treatment and edge to edge meeting in a straight line without merging.

Previous attempts to produce a device which would give the above-mentioned desirable results have not been entirely successful. They have not been able to apply films edge to edge in a straight line without merging and they must

2

be used on a rigid surface, usually plate glass, which cannot be conveniently stored.

The present invention may be used for applying films to rigid panels, as in the past, or to thin flexible sheets of material, such as paper, celluloid and the like. Two or more films may be applied simultaneously edge to edge in a straight line without merging in a quick and convenient manner.

10 Other objects and features of the invention will appear from the accompanying description with reference to the drawings, in which:

Figure 1 is a perspective view of the film applicator,

15 Figure 2 is a longitudinal section taken through the applicator,

Figure 3 is an elevation, partly broken away, of a part of the invention which may be used by itself, and

20 Figure 4 is a bottom plan view of the device shown in Figure 3.

Referring more particularly to the drawings, 10 is a block preferably of rectangular form. This block has two or more hoppers 11 arranged 25 side by side at one edge thereof and opening outwardly at its edge. Each hopper is separated from the adjacent hopper by a thin partition 12, the lower edge of which tapers downwardly to a very fine edge 13, see Figure 3.

30 A transverse slot 15 is formed in the bottom of each hopper and the bottom 16 of the hopper slopes towards said slot, as clearly shown in Figure 2. The slots 15 of the hoppers are in line with each other.

35 A vertical doctor blade 20 extends the combined length of the slots and is spaced above the lower surface of the hoppers, as shown at 21. As shown, the slot of each hopper is preferably formed in the bottom thereof at its outer side 40 in relation to the block and the doctor blade is mounted on the edge of the block so that it forms the outer wall of the hoppers with its lower edge at the slots thereof.

The blade may be formed with elongated slots 45, 23 through which set screws 24 extend. These screws may be screwed into the block to hold the doctor blade in any adjusted position. With this arrangement, the blade may be adjusted vertically in relation to the bottom of the block at the slots.

A pressure area 30 is formed on the bottom of the block 10 along the inner side of the slots 15, see Figures 2 and 4. This pressure area extends across the bottom of the block and, if desired, extensions 31 thereof may lie parallel with

and spaced from the ends of the block. The purpose of these extensions is to maintain the block in a position parallel to the surface on which it rests. The extensions are preferably spaced inwardly from the ends of the block to allow for any unevenness at the edges of the material therebeneath, although this is not absolutely necessary. Actually, the bottom 32 of the block is spaced above the pressure area so that any pressure applied to the top of the block is transmitted therethrough to said pressure area only.

The block 10 may be used by itself to form films of two or more different materials, the block illustrated being adapted to form two films. When used in this manner, it is preferable to apply films to a panel formed of rigid material, such as plate glass. When the block rests on the panel, the pressure area 30 bears against said panel. The doctor blade 20 may be adjusted vertically to provide a space 33 below its lower edge of a desired thickness, which represents approximately double the thickness of the film to be applied. Then a small quantity of the two materials to be compared are placed separately in the hoppers 11. The material in the hoppers fills the slots 15 and rests on the panel. When the block is moved over the panel in the direction of arrow A in Figure 2, or as the panel is moved in the direction of arrow B, the material tends to adhere to the panel and is drawn through the space beneath the doctor blade, at which time the upper surface of the material tends to adhere to the lower edge of the blade, thus shearing the material substantially midway between the blade edge and the panel. The thickness of the resulting films is equal to approximately half the depth of the space beneath the doctor blade. Films of the two materials are applied at exactly the same time and are exactly the same thickness. They are also side by side and the tapered lower edge of the partition 12 allows the two films to come into contact without actually merging with each other. Thus the color and density of the two materials may be accurately compared.

The block 10 may be used in conjunction with a base 38 having a flat top and vertical walls 39 at the opposite sides thereof. In this form of the invention the block 10 is preferably provided with pins 40 projecting outwardly from its opposite ends adapted to fit into slots 41 formed in the walls 39. The slots 41 are designed to prevent the block from moving towards either edge of the base. If desired, suitable means may be provided for holding the pins in the slots, such as, for example, spring arms 42 pivotally mounted at 43 on the upper edges of the walls and adapted to be moved over the pins 40. When the block is resting on the base, it is preferable that the upper surfaces of the pins lie above the upper edges of the side walls in order that the spring arms 42 may exert a certain amount of pressure downwardly on the arms.

This arrangement is particularly adapted for use with thin sheets of material 45, such as paper. The block 10 and its associated elements function as described above. A piece of paper is laid over the base 38 between its side walls with one end projecting outwardly beyond the edge of the base. Then the block is placed on the paper with its pins 40 resting in the slots 41 and the spring arms bearing down on said pins. When the materials to be compared are placed in the hoppers 11, the piece of paper 45 is drawn in the direction of the arrow B, at which time a thin film of each

material is formed on the paper. The pressure area 30 bears against the piece of paper or panel to retain it the predetermined distance from the lower edge of the doctor blade. Here again, the films are formed side by side without merging at the same time, and are of exactly the same thickness. The adjacent edges of the two films form a straight line, thus making it relatively easy to compare the two films in the usual manner. The sheets of material used in this example are relatively inexpensive and may easily and conveniently be stored for future reference.

What I claim as my invention is:

1. A film applicator comprising at least two hoppers arranged side by side, a thin partition between the hoppers, a narrow transverse slot in the bottom of each hopper at one edge thereof, said slots being aligned with each other, and the bottoms of the hoppers sloping towards their respective slots, a vertical doctor blade extending the combined length of the slots and forming a wall for the hoppers, the lower edge of said blade being spaced above the lower surface of the hoppers, and means for vertically adjusting the doctor blade.

2. A film applicator comprising a block, at least two hoppers formed side by side in the block at one edge thereof and opening outwardly at said edge, a transverse slot in the bottom of each hopper at the edge of the block, said slots being aligned with each other, a thin partition between the hoppers, said partition tapering down to a very fine edge between the slots, and a doctor blade forming the outer wall of the hoppers with its lower edge at the slots thereof.

3. A film applicator comprising a block, at least two hoppers formed side by side in the block at one edge thereof and opening outwardly at said edge, a thin partition between the hoppers, a transverse slot in the bottom of each hopper at the edge of the block, said slots being aligned with each other, and the bottoms of the hoppers sloping towards their respective slots, a doctor blade forming the outer wall of the hoppers with its lower edge at the slots thereof, and means for vertically adjusting the doctor blade in relation to the slots.

4. A film applicator comprising a block, at least two hoppers formed side by side in the block at one edge thereof and opening outwardly at said edge, a thin partition between the hoppers, a transverse slot in the bottom of each hopper at the edge of the block, said slots being aligned with each other, a doctor blade forming the outer wall of the hoppers with its lower edge at the outer side of the slots, and a pressure area formed on the bottom of the block along the inner side of the slots.

5. A device according to claim 4 in which the pressure area is a relatively narrow strip extending along the inner side of the slots and its lower surface is spaced below the bottom surface of the block.

6. A film applicator comprising a base, a block adapted to rest on the base, means for retaining the block in position on the base, at least two hoppers formed side by side in the block at one edge thereof and opening outwardly at said edge, a thin partition between the hoppers, a transverse slot in the bottom of each hopper at the edge of the block, said slots being aligned with each other, and a doctor blade forming the outer wall of the hoppers with its lower edge at the slots thereof and terminating above the base.

7. A film applicator comprising a base, a block

adapted to rest on the base, means for removably retaining the block in position on the base, at least two hoppers formed side by side in the block at one edge thereof and opening outwardly at said edge, a thin partition between the hoppers, a transverse slot in the bottom of each hopper at the edge of the block, said slots being aligned with each other, a doctor blade forming the outer wall of the hoppers with its lower edge at the slots thereof and terminating above the base, and means for vertically adjusting the doctor blade.

8. A film applicator comprising a block, at least two hoppers formed side by side in the block, a thin partition between the hoppers, a transverse slot in the bottom of each hopper, said slots being aligned with each other, a vertical doctor blade mounted on the hoppers and forming a wall therefor with its lower edge in the slots thereof and terminating above the bottom of the block, and a flat pressure area formed on and extending across the bottom of the block beneath the hoppers at the sides of the slots thereof remote from the blade, said pressure area being lower than any other part of the block.

9. A film applicator comprising a block, a flat pressure area formed on and extending across the bottom of the block adjacent one edge thereof, said pressure area being lower than any other part of the block, at least two hoppers formed side by side in the block and opening outwardly at the edge thereof adjacent which the pressure area is located, a thin partition between the hoppers, a transverse slot in the bottom of each hopper between the pressure area and the block edge, said slots being aligned with each other, and a doctor blade forming the outer wall of the hoppers with its lower edge at the outer side of the slots and normally above the pressure area.

10. A film applicator as claimed in claim 9 in which the pressure area also extends along each side of the bottom of the block.

11. A film applicator comprising a base, a block adapted to rest on the base, means for retaining the block in position on the base, at least two hoppers formed side by side in the block at one edge thereof and opening outwardly at said edge, a thin partition between the hoppers, a transverse slot in the bottom of each hopper at the edge of the block, said slots being aligned with each other, a doctor blade forming the outer wall

of the hoppers with its lower edge at the outer side of the slots, and a flat pressure area formed on the bottom of the block along the inner side of the slots, said pressure area being lower than any other part of the block and adapted to rest on the base.

12. A film applicator comprising a base, a block adapted to rest on the base, means for retaining the block in position on the base, a flat pressure area formed on and extending across the bottom of the block adjacent one edge thereof, said pressure area being the only part of the block engaging the base, at least two hoppers formed side by side in the block and opening outwardly at the edge thereof adjacent which the pressure area is located, a thin partition between the hoppers, a transverse slot in the bottom of each hopper between the pressure area and the block edge, said slots being aligned with each other, and a doctor blade forming the outer wall of the hoppers with its lower edge at the outer side of the slots and normally above the pressure area and the base.

13. A film applicator comprising a base having a flat top, vertical walls at the opposite sides of the base having slots therein, a block adapted to rest on the base between the side walls of the latter, pins projecting outwardly from the opposite ends of the block and fitting into the wall slots, a spring arm on each wall adapted to bear on the block pin in the slot of its wall, at least two hoppers formed side by side in the block, a thin partition between the hoppers, a transverse slot in the bottom of each hopper, said slots being aligned with each other, and a vertical doctor blade mounted on the hoppers and forming a wall therefor with its lower edge in the slots thereof and terminating above the bottom of the block and the base.
